ATTY.

UNITED STATES PATENT OFFICE.

CECIL MURRAY BOYCE, OF WESTCLIFF-ON-SEA, ENGLAND.

DESIGN FOR AN AIR-PUMP-NOZZLE CONNECTION.

55,975.

Specification for Design.

Patented Aug. 10, 1920.

Application filed November 8, 1919. Serial No. 336,767. Term of patent 7 years.

To all whom it may concern:

Be it known that I, CECIL MURRAY BOYCE, a subject of the King of Great Britain and Ireland, residing at 306 London road, Westcliff-on-Sea, Essex, England, have invented a new, original, and ornamental Design for an Air-Pump-Nozzle Connection, of which the following is a specification, reference being had to the accompanying drawing, forming part thereof.

The figure is a side elevation of an air pump nozzle connection, as shown.

I claim the ornamental design for an air pump nozzle connection as shown.

CECIL MURRAY BOYCE.
